UNITED STATES PATENT OFFICE

WALTER D. KELLER AND WILLIAM L. POTO, OF ALLIANCE, OHIO, ASSIGNORS TO THE
ALLIANCE MACHINE COMPANY, OF ALLIANCE, OHIO, A CORPORATION OF OHIO

INGOT-STRIPPING MECHANISM

Application filed September 4, 1928. Serial No. 303,770.

This invention relates to ingot stripping mechanism, and particularly to ingots cast with the larger end up, also known as inverted type ingots.

5 Ingots are made of tapering form to facilitate the stripping thereof from the ingot mold. It was formerly universal practice to cast ingots with the small end up, but in recent years this practice has been reversed in 10 many plants, the ingots being cast with the large end up. The stripping means formerly employed cannot be used for stripping inverted type ingots as with this type it is necessary to hold the mold down and exert an 15 upward pressure on the ingot by means of a ram.

The inverted type of ingot is usually cast with a mold having a "hot top" which when removed leaves a projecting portion of the 20 ingot projecting above the top of the mold proper. This projecting portion is engaged by the tongs of the ingot crane. In a large number of cases the ingot lifts freely from the mold and need not be stripped. However, in regular operation there are always 25 cases where "stickers" are encountered and the ingot must be stripped.

In practice, the projecting tops of the ingots are engaged by the tongs to determine 30 whether or not the ingot needs to be stripped. If the ingot is loose in the mold the tongs are disengaged and the crane is moved to the next mold. It has heretofore been the practice to use a stationary stripper, and in case 35 a sticker is encountered to pick up the ingot and the mold with the crane and carry it to the stripper. The stripping operation with such apparatus is unsatisfactory and inefficient, due to the excessive amount of crane 40 travel required to carry the ingots and molds to and from the stripper.

We provide a travelling stripper for inverted type ingots. Preferably an overhead crane bridge is employed, this bridge carrying 45 an ingot crane and the stripper. The bridge runs in the direction of the tracks on which the ingot cars are handled, and it is a relatively simple matter to move the crane along to test whether or not the ingots need stripping. When a sticker is encountered the 50

crane picks up the ingot and the mold and carries it to the stripper. The amount of movement is relatively small, being at the most the length of the bridge. The ingot is then stripped and the mold is returned to 55 the car.

In the accompanying drawings, illustrating the present preferred embodiment of our invention,

Figure 1 is a side elevation of a crane and 60 stripper constructed according to our invention, and

Figure 2 is a vertical transverse section taken on the line II—II of Figure 1.

In the drawings there is shown a series of 65 tracks 2 for ingot cars 3 carrying ingot molds 4. The molds contain cast ingots and the hot tops have been removed, leaving a projecting portion 5.

Overhead crane tracks 6 are provided, 70 these tracks extending in the same direction as the tracks 2.

A crane bridge 7 extends between the tracks 6. The bridge consists of spaced girders 8 connected at the ends by trucks 9 carrying 75 track wheels 10 running on the rails 6. The girders 8 carry rails 11 which support a trolley 12 movable longitudinally of the bridge 7. The trolley 12 is of well known type embodying a stiff leg 13 having tongs 14 at the 80 bottom thereof.

Projecting downwardly from each girder 8 are spaced legs 15 connected by structural bracing 16 on three sides to form a rigid structure. The side of this structure adjacent 85 the tracks 2 is open so that the downwardly projecting portions on the trolley 12 can enter the structure as indicated in chain lines in Figure 1.

A stripper, indicated generally by the reference character 17, is carried at the bottom of the legs 15. This stripper comprises a base 18 adapted to support an ingot mold M and hooks 19 adapted to be swung into position to engage ears 20 on the ingot mold M. 90 Below the support 18 is a cross frame 21 carrying a plunger 22. When an ingot mold is placed on the support 18 and held down by the hooks 19, upward movement of the cross frame 21 forces the plunger against the bot- 95 100

tom of the ingot, thus stripping it from the ingot mold. This upward movement is effected by cables 23 extending around sheave wheels 24 on the cross frame 21 and sheave wheels 25 on the fixed structure carried by the legs 15. One end of each cable is dead-ended on the frame and the other end is wrapped on a winding drum 26 driven through gearing 27 by a motor, not shown.

5 10 When a sticker is encountered it is picked up by the tongs 14 and placed on the support 18. It is held down by the hooks 19 and the cross frame 21 is then moved upwardly to strip the ingot from the mold. After the stripping operation the mold, with 15 the loosened ingot therein, is returned to the ingot car and is ready to be taken to the soaking pit crane.

20 We have illustrated and described the present preferred embodiment of our invention, but it will be understood that it is not limited to this form alone, but may be otherwise embodied within the scope of the following claims.

25 We claim:—

1. An overhead travelling crane and a stripper for inverted-type ingots carried thereby, the stripper having a portion which engages the bottom of the ingot for stripping it, the crane being adapted to transfer an ingot and its mold onto the stripper.

2. An overhead travelling crane having a bridge and a trolley, the bridge having a downward extension, and a stripper for inverted-type ingots carried on said extension, the crane trolley being movable into position to deposit an ingot and its mold on the stripper.

3. In combination with an ingot car track, 40 a crane travelling longitudinally of the track, and a stripper for inverted-type ingots movable with the crane, the stripper having a portion which engages the bottom of the ingot for stripping it, the crane being adapted 45 to transfer an ingot and its mold to the stripper.

4. An overhead travelling crane bridge, a crane trolley carried thereby, and a stripper for inverted type ingots carried by the bridge, 50 the crane trolley being movable into vertical alignment with the stripper.

5. A travelling crane bridge, an open sided supporting structure carried thereby, a stripper for inverted type ingots on said structure, and a crane trolley carried by the crane bridge and movable to a point within the open sided structure.

6. Apparatus for stripping inverted type 60 ingots, comprising overhead spaced crane girders, a trolley carried by the girders and having ingot lifting means therebetween, members extending downwardly from the girders, the ingot lifting means being movable between such members so as to deposit

on the stripper an ingot to be stripped, and a stripper carried by said members.

7. Apparatus for stripping inverted type ingots, comprising an overhead traveling crane, and a stripper for inverted ingots movable therewith, the crane being adapted to handle a mold to or from the stripper.

8. Apparatus for stripping inverted type ingots, comprising a movable frame, a stripper for inverted type ingots carried thereby, 75 and a crane trolley carried by the frame and adapted to handle a mold to or from the stripper.

9 In testimony whereof we have hereunto set our hands.

WALTER D. KELLER.
WILLIAM L. POTO.
